Primary Examiner — Jennifer L Watkins*Assistant Examiner* — Samantha Lynne Brodowski(74) *Attorney, Agent, or Firm* — Bycer Law, PLC;
Matthew L. Bycer(57) **CLAIM**

The ornamental design for a multiple directional wheel rim, as shown and described.

DESCRIPTION

FIG. 1 is a front plan view of a multiple directional wheel rim according to the present design;

FIG. 2 is a bottom side elevation view thereof;

FIG. 3 is a rear plan view thereof;

FIG. 4 is a front perspective view thereof;

FIG. 5 is a left side elevation view thereof; and,

FIG. 6 is a top side elevation view thereof.

The dashed lines in the drawings depict the claim boundary. All of the subject matter inside of the dashed lines forms no part of the claim.

1 Claim, 6 Drawing Sheets(56)
